(57) **CLAIM**

The ornamental design for pair of ear buds, as shown and described.

DESCRIPTION

FIG. 1 is a perspective view of the top front perspective view (right ear bud) of a pair of ear buds showing my new design; FIG. 2 is a front (Right Ear Bud) view thereof.

FIG. 3 is a rear (Right Ear Bud) view thereof.

FIG. 4 is a left (Right Ear Bud) view thereof.

FIG. 5 is a right (Right Ear Bud) view thereof.

FIG. 6 is a top (Right Ear Bud) view thereof.

FIG. 7 is a bottom (Right Ear Bud) view thereof.

FIG. 8 is a top front perspective view (left ear bud) of a pair of ear buds showing my new design;

FIG. 9 is a front (Left Ear Bud) view thereof.

FIG. 10 is a rear (Left Ear Bud) view thereof.

FIG. 11 is a left (Left Ear Bud) view thereof.

FIG. 12 is a right (Left Ear Bud) view thereof.

FIG. 13 is a top (Left Ear Bud) view thereof; and,

FIG. 14 is a bottom (Left Ear Bud) view thereof.

The features shown in broken lines depict environmental subject matter only and form no part of the claimed design.

1 Claim, 8 Drawing Sheets
